UNITED STATES PATENT OFFICE

ALVIN C. SEIDE, OF BROOKLYN, NEW YORK

DESIGN FOR A GLOVE OR SIMILAR ARTICLE

Application filed January 21, 1932. Serial No. 42,583. Term of patent 3½ years.

To all whom it may concern:

Be it known that ALVIN C. SEIDE, a citizen of the United States, and resident of Brooklyn, in the county of Kings and State of New York, has invented a new, original, and ornamental Design for Glove or Similar Article, of which the following is a specification, reference being had to the accompanying drawings forming part thereof, in which,

Fig. 1 is a perspective view of a glove embodying my new design; and

Fig. 2 is a detail sectional view taken along line 2—2 of Fig. 1.

I claim:

The ornamental design for a glove or similar article, substantially as shown.

Dated, January 20th 1932.

ALVIN C. SEIDE.
